UNITED STATES PATENT OFFICE.

IREDELL EACHUS, OF PHILADELPHIA, PENNSYLVANIA, ASSIGNOR TO THE MACBETH
ARC LAMP COMPANY, INC., OF PHILADELPHIA, PENNSYLVANIA, A CORPORATION
OF PENNSYLVANIA.

DESIGN FOR AN ARC-LAMP CASING.

52,211.

Specification for Design.

Patented July 23, 1918.

Application filed April 28, 1916. Serial No. 94,271. Term of patent 7 years.

To all whom it may concern:

Be it known that I, IREDELL EACHUS, a citizen of the United States, residing at Philadelphia, in the county of Philadelphia, State of Pennsylvania, have invented a new, original, and ornamental Design for an Arc-Lamp Casing, of which the following is a specification, reference being had to the accompanying drawing, forming part thereof.

Figure 1 is a perspective view of an arc lamp casing showing my new design.

Fig. 2 is a front view of the same lamp.
I claim:

The ornamental design for an arc lamp casing, as shown.

IREDELL EACHUS.

Witnesses:

W.M. STEELL JACKSON,
J. LUTHERIA KAUFFMAN.
